UNITED STATES PATENT OFFICE.

ARTHUR SOLOMON, OF NEW YORK, N. Y.

DESIGN FOR TEXTILE FABRIC.

Application filed July 17, 1928. Serial No. 27,510. Term of patent 3½ years.

To all whom it may concern:

Be it known that I, ARTHUR SOLOMON, a citizen of the United States, residing at New York, in the county of New York and State of New York, have invented a new, original, and ornamental Design for a Textile Fabric, of which the following is a specification, reference being had to the accompanying drawing, forming part thereof.

The figure is a face view of textile fabric showing my new design.

I claim:

The ornamental design for textile fabric as shown.

In testimony whereof I have affixed my signature.

ARTHUR SOLOMON.
